UNITED STATES PATENT OFFICE.

SAMUEL BRAINERD CLAY, OF ST. LOUIS, MISSOURI, ASSIGNOR TO HEINE BOILER COMPANY, OF ST. LOUIS, MISSOURI, A CORPORATION OF MISSOURI.

TOOL FOR INSTALLING BOILER HANDHOLE CAPS.

Application filed August 4, 1923. Serial No. 655,674.

To all whom it may concern:

Be it known that I, SAMUEL B. CLAY, a citizen of the United States, residing at St. Louis, Missouri, have invented a certain 5 new and useful Improvement in Tools for Installing Boiler Handhole Caps, of which the following is a full, clear, and exact description, such as will enable others skilled in the art to which it appertains to make 10 and use the same.

This invention relates to tools of the kind that are used for exerting endwise pressure on an article that is positioned in a member, either to unseat the article or to 15 seat the article firmly in said member.

The main object of my invention is to provide a tool of the type referred to that is easy to handle and operate, and which is equipped with an hydraulic or fluid operated means for causing the jaws of the tool 20 to engage the article being seated or unseated and for thereafter moving said jaws in a direction to shift the article endwise or longitudinally relatively to the member 25 in which the article is positioned.

I have herein illustrated my invention embodied in a tool that is designed to be used for installing boiler hand hole caps of the type that consists of a hollow, cup-shaped member provided with a hollow 30 tapered portion that projects through a hand hole in one wall of the water leg of a boiler, but I wish it to be understood that the tool can be used for various other 35 purposes and that changes can be made in the construction and arrangement of the parts of the tool without departing from the spirit of my invention.

Figure 1 of the drawings is a longitudinal 40 sectional view of my improved tool, with the jaws of the tool shown in elevation.

Figure 2 is a longitudinal sectional view of the jaws and certain other parts of the tool that are associated with the jaws; and 45

Figure 3 is an end view of the jaws and the tapered element which the jaws surround.

In the drawings *x* designates a boiler 50 hand hole cap that is provided with a tapered portion which projects forwardly through a hand hole in the front wall *y* of a boiler water leg, said cap *x* being temporarily positioned in the hand hole by arranging the cap inside of the water leg 55 and then manually forcing the tapered por-

tion of the cap forwardly through the hand hole. Thereafter the cap *x* is drawn tightly into the hand hole by the aid of my improved tool so as to produce a steam-and-water tight joint between the tapered portion 60 of the cap and the part *y* of the boiler in which the cap is positioned.

My improved tool is of such design that the jaws of the tool can be introduced into the hand hole cap without liability of dislodging the cap from its temporary position, and a controlling valve thereafter manipulated so as to cause an hydraulic or fluid operating medium to act on parts of the tool in such a way as to expand the 70 jaws and hold them pressed tightly against the tapered portion of the cap and thereafter move said jaws in a direction to seat the cap tightly in the hand hole which it 75 closes. The main elements of the tool consist of jaws *A*, of any suitable design, constructed so that they can be collapsed and introduced into the cap *x*, a member *B* adapted to be arranged in engagement with the front sides of the part *y* of the boiler 80 in which the cap is positioned, a cylinder *C* carried by the member *B* and provided with a piston *D* that is connected by means of a piston rod *E* with an element *F* which the jaws surround, a second piston *D'* that actuates a device *G* which is used to expand the jaws and also to effect the collapsing of the jaws, and a valve *H* that is adapted 85 to be opened so as to cause an operating medium which may be a liquid or a fluid under pressure, to act first on the piston *D'* to cause the jaws *A* to be expanded into engagement with the tapered portion of the hand hole cap *x* and thereafter act on the piston *D* and move it longitudinally of its cylinder *C* in a direction to cause the jaws 90 to exert endwise pressure on the hand hole cap in a direction to seat the cap tightly in the part *y* of the boiler.

During the operation of installing a hand hole cap the tool is supported by an operator who grasps a handle *I*, connected to the member *B* and to the cylinder *C*, and a knurled hand grip *J* on a forwardly-projecting portion of the piston rod *E*, the member *B* of the tool being of such design that when the inner end of same is pressed against the outer face of the part *x* of the boiler in which the hand hole cap is positioned, the piston *D* will be arranged in front of said part *y* 100

in parallel relation to same and the piston rod E which carries the jaws of the tool will be arranged in longitudinal alignment with the center line of the hand hole cap x. The 5 piston rod E projects rearwardly through the end wall of the cylinder C and the inner end of said piston rod is connected, preferably rigidly, to the element F which the jaws A surround. The element F of the tool here- 10 in illustrated is of substantially frusto-conical shape in outline, and the jaws A are of segmental shape and provided on their inner sides with inclined surfaces that bear against the tapered outer face of the element F, the jaws being held together and retained in 15 sliding engagement with the tapered element F by one or more annular resilient retaining devices 1 that are arranged in grooves in the outer side of the jaws A. When the jaws A move longitudinally of the tapered element F, towards the small end of said element, they will collapse or contract, and when said 20 jaws move longitudinally of the element F in the opposite direction, they will expand, the element F being provided adjacent its 25 large end with an annular rib 2 that forms an abutment which co-operates with shoulders 3 on the jaws A to limit the outward movement of said jaws when they are expanded. The device G previously referred 30 to that governs the expansion and contraction of the jaws A preferably consists of a sleeve reciprocatingly mounted on a cylindrical guide 4 at the small end of the tapered 35 element F and arranged so that it bears against the inner ends of the jaws A, as shown in Figure 2, said sleeve G being adapted to be moved longitudinally in one direction to expand the jaws and in the opposite direction to permit the jaws to be collapsed by the pressure which the resilient 40 retaining devices 1 exert on the jaws in a direction tending to cause them to move towards the small end of the tapered element F.

The piston rod E is hollow and the piston D', previously referred to, is reciprocatingly mounted in said piston rod, or rather in the cylindrical guide 4 that virtually forms part 50 of the piston rod, and is connected by means of a cross pin 5 to the sleeve G which surrounds the guide 4, said guide having elongated slots 6 therein that receive the pin 5 and thus permit the piston D' and sleeve G 55 to move longitudinally with relation to the piston rod. As shown in Figures 1 and 2, the hollow piston rod E is provided with orifices 7 arranged adjacent the point where the piston D is connected to said rod, so as to 60 cause the operating medium that is admitted to the piston rod E from the supply pipe 8 to escape laterally into the cylinder C at a point between the piston D and the end wall of said cylinder, and thus move said piston longitudinally in one direction. Move-

ment of said piston D in the opposite direction is effected by an expansion spring 9 that acts on the piston, and movement of the piston D' longitudinally in one direction is effected by an expansion spring 10 that is arranged in a center bore in the tapered element F in such a way that it bears against one end of the piston D'.

After the cap x has been temporarily positioned in the part y of the boiler, the jaws A of the tool which are then collapsed, are introduced into the cap and the member B of the tool pressed against the front side of the part y of the boiler in which the cap is positioned. Thereafter, the valve H is manipulated so as to permit the operating medium to pass from the supply pipe 8 into the hollow piston rod E and exert pressure on the piston D' in a direction to cause the sleeve G that is connected with said piston to move the jaws A longitudinally towards the large end of the tapered element F, the co-operating inclined surfaces on said element F and on said jaws causing the jaws to be forced outwardly into clamping engagement with the tapered portion of the hand hole cap. As soon as the jaws A have been expanded, due to the pressure which the operating medium exerts on the piston D', said operating medium escapes through the orifices 7 in the piston rod and exerts pressure on the piston D in a direction to move said piston D and the jaws A with which it is connected, longitudinally in a direction to draw the cap x tightly into the hand hole in the part y of the boiler. After the cap has been seated in the part y of the boiler, the valve H is manipulated so as to permit the operating medium to escape from the cylinder C and from the hollow piston rod, whereupon the piston D will move longitudinally in the opposite direction, under the influence of the spring 9, and the jaws A will move into their collapsed position, due to the pressure which the resilient jaw retaining devices 1 exert on the jaws in a direction to cause the jaws to move longitudinally towards the small end of the tapered element F, it being understood that as soon as the pressure of the operating medium on the piston D' is relieved, the spring 10 will expand and move said piston D' and the sleeve G longitudinally in a direction to permit the jaws A to slide over the tapered surface of the element F towards the small end of the same.

A tool of the construction above described is reliable in operation, it is of simple design, it enables a boiler hand hole cap to be seated tightly in a hand hole in a fraction of the time that is required to seat a hand hole cap with a manually-operated tool, and the jaws of the tool are so constructed and operated that they will be completely collapsed at the time they are introduced into the hand

hole cap, thereby eliminating the possibility of the jaws bearing against the cap and dislodging it from its temporary position during the operation of inserting the jaws in the cap.

Having thus described my invention, what I claim as new and desire to secure by Letters Patent is:

1. A tool for moving an article endwise of a part in which the article is positioned, comprising jaws that are adapted to be engaged with the article, a single valve that governs an operating medium, and means adapted to be actuated by said operating medium for causing said jaws to tightly grip the article and thereafter move the article endwise with relation to the part with which it is positioned when said valve is opened.

2. A tool for moving an article endwise of a part in which the article is positioned, comprising jaws that are adapted to be engaged with the article, two pistons, and a single means that is adapted to be actuated to cause an operating medium to act on one of said pistons, thereby causing the jaws to tightly grip the article and to thereafter act on the other piston and exert pressure on the jaws in a direction tending to move the article endwise relatively to the part in which it is positioned.

3. A tool for moving an article endwise of a part in which the article is positioned, comprising jaws that are adapted to be engaged with the article, a piston for causing said jaws to tightly grip the article, a second piston for moving the jaws so as to shift the article longitudinally with relation to the part in which it is positioned, and means that is adapted to be operated for causing an operating medium from a single source of supply to act on both of said pistons, said pistons being so proportioned and arranged that the piston which causes the jaws to grip the article will operate in advance of the other piston.

4. A tool for the purpose described, comprising a cylinder provided with a piston, a hollow piston rod connected to said piston, jaws carried by said piston rod, a second piston reciprocatingly mounted in said piston rod for expanding said jaws, and means whereby the admission of an operating medium to said piston rod causes the piston therein to expand the jaws and thereafter causes the other piston to move in a direction to move the piston rod and jaws endwise.

5. A tool for the purpose described, comprising a cylinder provided with a piston, a hollow piston rod connected to said piston, jaws associated with said piston rod, a piston in said rod for expanding said jaws, an orifice in said piston rod that establishes communication between the interior of

same and the interior of said cylinder whereby the admission of an operating medium to said piston rod causes the piston in said rod to act and thereafter causes the piston in said cylinder to act, and means for collapsing said jaws when the piston in the piston rod is not subjected to the pressure of the operating medium.

6. A tool for installing boiler hand hole caps, comprising a member adapted to be arranged in engagement with the part of the boiler in which the cap is positioned, a cylinder carried by said part and provided with a piston, a piston rod connected to said piston, expandable jaws combined with said piston rod and adapted to be introduced into the cap, a second piston for expanding said jaws, and means whereby the operation of opening a single controlling valve causes an operating medium to act on said pistons in such a way as to cause the jaws to tightly grip the cap and thereafter draw the cap tightly into its seat.

7. A tool for installing hand hole caps in boilers, comprising a member adapted to be arranged in engagement with a part of the boiler in which the cap is positioned, a cylinder on said member provided with a piston, a hollow piston rod connected with said piston, expandable jaws combined with said piston rod and adapted to be introduced into the cap, a second piston in said piston rod for expanding said jaws, and an orifice in said piston rod that establishes communication between the interior of same and said cylinder, whereby the admission of an operating medium to said piston rod causes the jaws to be expanded into engagement with the cap and the jaws thereafter moved in a direction to seat the cap.

8. A tool for installing hand hole caps in boilers, comprising a member adapted to be arranged in engagement with the part of the boiler in which the cap is positioned, a cylinder on said member provided with a piston, a hollow piston rod connected to said piston, a tapered element combined with said piston rod, expandable jaws surrounding said tapered element and adapted to be introduced into the cap, means that tend to normally hold said jaws collapsed, a second piston in said piston rod for expanding said jaws, and means for permitting an operating medium that is supplied to said piston rod to escape into said cylinder and actuate the piston in said cylinder.

9. A tool for installing boiler hand hole caps, comprising a member adapted to be arranged in engagement with a part of the boiler in which the cap is positioned, a cylinder on said member provided with a piston, a hollow piston rod connected to said piston, a tapered element combined with said piston rod, jaws surrounding said tapered element and adapted to be collapsed

by movement longitudinally of said element in one direction and to be expanded by movement longitudinally of said element in the opposite direction, a second piston in said piston rod for expanding said jaws, and an orifice in said piston rod that establishes communication between the interior of same and said cylinder.

10. A tool for installing boiler hand hole caps, comprising a member that is adapted to be arranged in engagement with a part of the boiler in which the cap is positioned, expansible jaws that are adapted to be in-

duced into the cap, a single controlling valve for governing an operating medium, means whereby the operation of opening said valve expands the jaws into engagement with the cap and thereafter causes the jaws to exert pressure on the cap in a direction to seat it tightly in the part of the boiler which carries same, and means for disengaging the jaws from the cap after the valve has been manipulated to cut off the supply of the operating medium.

SAMUEL BRAINERD CLAY.
